(57) **CLAIM**

The ornamental design for a mobile phone, as shown and described.

DESCRIPTION

FIG. 1 is a front perspective view of a mobile phone showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The evenly-spaced dashed broken lines in the drawings depict environmental subject matter and portions of the mobile phone that form no part of the claimed design. The dot dash broken lines in the figures represent the bounds of the claimed and form no part thereof. The appearance of any portion of the article between the pairs of the dot-dash broken lines forms no part of the claimed design.
